UNITED STATES PATENT OFFICE

MORRIS SALINGER, OF NEW YORK, N. Y., ASSIGNOR OF ONE-HALF TO EMANUEL D. STEIN, OF NEW YORK, N. Y.

DESIGN FOR A CLOCK HAND OR SIMILAR ARTICLE

Application filed January 31, 1929. Serial No. 29,857. Term of patent 14 years.

To all whom it may concern:

Be it known that I, MORRIS SALINGER, a citizen of the United States, residing at New York city, county of Bronx, and State of New York, have invented a new, original, and ornamental Design for a Clock Hand or Similar Article, of which the following is a specification, reference being had to the accompanying drawings, forming a part thereof.

The figure is an elevational view of a clock hand or similar article, showing my new design. The dot and dash lines merely show how the design appears when applied to a conventional watch dial.

I claim:

The ornamental design for a clock hand or similar article, as shown.

MORRIS SALINGER,
